UNITED STATES PATENT OFFICE.

GEORGE W. HEENE, OF CLEVELAND, OHIO.

EMBOSSING AND PRINTING MACHINE.

Application filed December 10, 1923. Serial No. 679,607.

To all whom it may concern:

Be it known that I, GEORGE W. HEENE, a citizen of the United States, residing in Cleveland, county of Cuyahoga, and State of Ohio, have invented a new and useful Embossing and Printing Machine, of which the following is a specification.

My invention relates to mechanisms for either embossing or printing, or for embossing and printing letters or numbers or other characters upon objects susceptible for or to such operations.

The main object of my invention is a simple, efficient, and easily operable and always ready mechanism to either emboss or to print, or to emboss and print, letters, numerals, or other characters upon objects susceptible for such operations. Other objects will appear during the description of the apparatus shown in the accompanying drawings.

In these accompanying drawings, I show one embodiment of my invention in a certain machine; it is understood, however, that modifications may be made within the scope of the appended claims.

In these accompanying drawings, Fig. 1 is a general perspective view of a complete machine for either embossing or for printing or for embossing and printing characters upon an object and embodying the features of my invention; Fig. 2 is a section, taken on a vertical plane indicated by the lines 2—2 in Fig. 1, showing sectionally the relations between the elements substantially on the vertical axis of the machine; Fig. 3 is a section, taken on a horizontal plane indicated by the lines 3—3 in Figs. 1 and 2 sectionally showing the relations of the die and typing or printing elements; Fig. 4 is an end view, indicated by the line 4 in Fig. 2, on a larger scale, partly in section, showing the lock mechanism for the type die wheel; Fig. 5 is a sectional view, on a larger scale, taken on a vertical plane indicated by the line 5—5 in Fig. 1, showing the embossing and typing mechanism; Fig. 6 is an end view of the left side of Fig. 1 showing the relations between the elements on this side of the machine; Fig. 7 is an end view of the table mechanism on a larger scale; Fig. 8 is an end view of the upper portion of the table indexing mechanism on a larger scale; Fig. 9 is a partial sectional view, taken on a vertical plane indicated by the line 9 in Fig. 3, showing

the shaft and crank arrangement at the lower end of the table indexing mechanism; Fig. 10 is a partial view showing the mechanism for indexing and locking the table. Fig. 11 is a sectional view, taken on a plane indicated by the line 11 in Fig. 1, showing the details of mounting a spool to permit the same to be removed when embossing without printing is to be performed.

Similar reference characters refer to similar parts throughout the views.

For the purpose of easy understanding of the machine shown in the drawings, it may be convenient to divide this machine into its main groups of elements of the housing, the typing mechanism, the table, and the table operating mechanism and describe the elements in connection with such grouping.

It is to be observed that embossing is understood to mean impressing characters into an object and that printing is understood to mean coloring the characters on the surface of the object as printing is usually understood.

The housing of this machine comprises the base 10, the brackets 11 secured to the base 10 in the present instance, and the lugs 12 and 13 projecting upward from the top of the brackets 11. The brackets 11 are U shaped to clear the loop 14 for the purpose appearing presently. The lug 12 is provided with the slot 15 and the lug 13 is provided with the groove 16. The bar 17 connects the upper ends of the lugs 12 and 13 and is secured thereto by the screws 18 and is provided with the handle portion 19 for conveniently carrying the machine. The tie bar 20 is secured to the lugs 12 and 13, on the front of the machine, by the screws 21 and is provided with the slot 22. The tie bar 23 is secured to the lugs 12 and 13, on the back of the machine, by the screws 24 and is provided with the slot 25.

As is clearly seen in Figs. 3 and 5, the typing mechanism comprises the type support member 26, the type wheel 27, and the operating mechanism therefor. One end of the type support member 26 is hinged to the lug 12 by the pin 28 and is disposed in the slot 15 while the other end thereof is provided with the tongue 29 extending into the groove 16 to guide the up and down movement of this free end of the member 26. The middle portion of the mem-

ber 26 is open to permit the introduction of the type wheel 27. The walls 30 are provided with the bosses 31 into which the shaft 32 is journaled. This other and free end 5 of the type support member 26 is provided with two apertures, countersunk therein, and the springs 33 are deposited therein. This free end is further provided with two holes, extending through this end, and the 10 guide pins 34 fit slidably therein. This free end is further provided with the pin 35 onto which is hooked one end of the spring (tension) 36 while the other end thereof is hooked onto the bar 17. The object of the 15 spring 36 is to normally hold this free end of the member 26 in its uppermost position as shown in full lines in the drawings.

The type wheel 27 is secured to the shaft 32 and rotates therewith, is confined between 20 the walls 30, and is provided with type dies 129 on the outer circumferential surface thereof. In the present instance, the type dies 129 are formed directly on the outer circumferential surface of the wheel 27 and 25 project beyond this outer surface sufficiently far to permit these dies to perform embossing operations. When printing operations only are to be performed, the screw 128 is adjusted to prevent these dies from embossing 30 the characters thereof more than necessary for such printing operations. In the present instance, these type dies are formed of the letters of the alphabet and the numerals 1 to 9; other or additional characters 35 may be substituted or added.

The knob 37 is secured to the front end of the shaft 32 while the toothed index wheel 38 is secured to the back end thereof.

As is clearly seen in Fig. 4, the bracket 39 40 is secured to the tie bar 23 and the middle portion thereof extends downward and is provided with the aperture 40 and with the opening 41. The compression spring 42 is disposed in the lower portion of the aperture 40 while the head 43 of the lock pin is disposed in the upper portion thereof adjacent the spring 42. The lower end of the lock pin extends through and is guided in the opening 41 in the lower end of the 45 bracket 39 and is provided with the pin 45 to limit the upward movement of the lock pin. The upper end of the lock pin is beveled both ways to engage the spaces between the teeth of the index wheel 38 when the 50 same moves downward as will appear presently.

The index disk 46 is secured to the shaft 32 and is provided with characters corresponding to the characters on the type dies 60 of the type wheel 27. The pointer 47 is secured to the tie bar 20 and extends over the index disk 46. It is observed that the type wheel and the index disk must be so related to each other that a certain character die 65 is located in the lowermost or operating posi-

tion when the pointer points to the same character at the top of the index disk.

As clearly seen in Figs. 1, 5, and 6; the operating mechanism for the typing mechanism comprises the shaft 48 journaled in the lug 13, the operating handle 49 secured to the outer end of the shaft 48, the cam 50 secured to the inner end of the shaft 48, and contacts the plate 51. The shaft 48 is so located in the lug 13 that the cam 50 bears 70 on the plate 51, as seen in Fig. 5, when this mechanism is at rest or in inoperative position.

The plate 51 rests on the springs 33, can move up and down, and is guided in this 80 movement by the guide pins 34 secured to the plate 51 and guided in the free end of the type support member 26.

The table 52 can move longitudinally on the guide ways 53 provided on the base 10 85 and is held down on these guide ways by the brackets 54 and 55 as clearly seen in Fig. 2. The rack 56 is secured to the front of the table 52 and is provided with gear teeth; the bracket 57 is also secured to the front face of the table 52 above the rack 56. The lugs 58 and 59 project outwardly from each end of the table 52; the lugs 58 having an opening therethrough for the guide pins 60 to slide up and down therein; the lugs 59 have the pins 61 onto which the lower end 90 of the tension spring 62 is hooked.

The clamping frame for holding the object to be operated upon (the book 63 shown in dot and dash lines for instance) 100 down upon the table comprises a pair of longitudinal bars 64 and 65 and a cross bar at each end of these longitudinal bars to complete the frame. Each of these cross bars, as clearly seen in Fig. 7, has the upper portion 66 secured to the respective ends of the bars 64 and 65, the loop portion 14 adjacent this portion 66, the lower portion 67 adjacent this loop portion and below this upper portion, and the guide portion 68 fitting between and guided in the lugs 58 and 59. The lower portion 67 is provided with the pin 69 onto which the upper end of the tension spring 62 is hooked. The object of the springs 62 is to pull the clamping frame 110 downward to clamp the object 63 down upon the table.

The shaft 70 is journaled in the table near the bottom of the lugs 58 and 59 and nearer to the lug 59 than to the lug 58. A cam 71 is secured to the shaft 70 near each end thereof and within the lugs 58 and 59. Each of these cams 71 is provided with the toe 72 abutting the inside of the lug 59 to hold the cam in position of rest or inoperative position as shown in full lines in Fig. 7. A handle 73 is secured to each end of the shaft 70 to rotate the same and operate the cams. The guide pins 60 are secured to the respective lower portions 67 of the frame and 120 125 130

form a guide for the same in relation to the table.

The loop portion 14 is provided to permit this machine to operate over all or any portion of a long sheet which may be rolled up and confined in these loops as the typing proceeds.

The table can be moved longitudinally by manual means and by indexing means operated by the type operating mechanism.

As clearly seen in Fig. 2, this manual table moving means comprises the shaft 74 journaled in the base 10, the gear 75 secured to the shaft 74 and extending through an opening in the top of the base and meshing with the rack 56, and the knob 76 to rotate the shaft 74. The index disk 77 is also secured to the shaft 74 and is provided with graduations to indicate the longitudinal position of the table in relation to the type wheel. The gear 75 and the disk 77 are so related to each other and to the rack 56 that the table is in central longitudinal position with the zero line therein directly under the operative position of one of the type dies when the pointer 78 registers with the "0" (zero) mark or graduation on the disk 77. The graduations on the disk 77 are so spaced that each graduation represents sufficient longitudinal movement of the table for proper spacing of the typing on the object 63.

The toothed wheel 79 is also secured to the shaft 74 and projects up through the top of the base 10 for automatic indexing of the table.

The bracket 80, carrying the pin 81, is secured to the top of the base 10. One end of the index bar 83 has the slot 84 to support this end on the pin 81 and permit the bar 83 to slide thereon.

As clearly seen in Figs. 2, 6, and 9, the index shaft 85 is journaled in the table 10. The crank 86 is secured to the shaft 85, near the front end, extends upward through the top of the base 10, and the other end of the bar 83 is hinged to the upper end thereof by the pin 87. This crank 86 also has the ear 88 onto which one end of the tension spring 89 is hooked. The other end of the spring 89 is hooked to the base 10.

The crank 90 is secured to the shaft 85, near the rear end thereof and extends out through the side of the base. The outer end of this crank 90 is provided with a boss 91 into which the lower end of the push rod 92 is mounted. The middle portion of this push rod 92 is bent into U form to clear the loops 14, the upper portion thereof fits slidably through and is guided in the bracket 93 which is rigid with the housing, and the upper end thereof is secured to the bracket 94 which is guided on the housing and adapted to move up and down thereon. The cam 95 is secured to the shaft 48, previously described in connection with the type op-

erating mechanism, is provided with the flat surface 96 normally resting on the top of the bracket 94, the high point 97, and the flat surface 98 concentric with the longitudinal axis of the shaft 48. The compression spring 99 is interposed between the brackets 93 and 94, over the rod 92.

As clearly seen in Fig. 10, the dog 100 is swivelly mounted on the pin 101 secured to the index bar 83 and is provided with the finger 102 adapted to engage the teeth on the wheel 79 when the automatic indexing mechanism is operating but is normally held out of engagement with these teeth, to permit manual operation to move the table. The spring 103 has one end thereof engaging the finger 102 and the other end thereof engaging the bar 83 for re-action, and the middle portion thereof is coiled around the pin 104 secured to the bar 83. The object of this spring is to normally exert a downward pressure on the outer end of the finger 102.

The dog 100 is further provided with the toe 105 projecting downward and abutting the end of the bracket 80 to normally hold the finger 102 out of engagement with the teeth on the wheel 79 against the action of the spring 103 while the bar 83 is not operating to permit the manual operation or rotation of the shaft 74.

The pins 106 are secured to the bar 83 and are spaced so that they enter between two pair of teeth of the wheel 79 and lock the same in indexed position while the typing mechanism is operating.

The object locating means shown comprises the guide member 107 extending transversely from the table and the guide member 108 extending transversely from the member 107. The guide member 107 consists of a body having the projections 109, 110, and 111. The space between the projections 110 and 111 fits loosely over the projecting flange 112 of the bracket 57 so that the member 107 can slide longitudinally thereon for adjustment. The screw 113 is journaled in the projection 109, is threaded into the projection 110, and the end thereof abuts the flange 112 to lock the guide apparatus in adjusted position longitudinally. The guide member 108 consists of a body having the notch 114 fitting slidably over the body of the member 107 and of the screw 115 threaded into the body and abutting the guide member 107 to lock the member 108 to the member 107 in adjusted position transversely.

The wire 116 is secured to each end of the frame and is disposed just ahead of the type dies to form a guide for locating the object to be operated upon when such operation is to be performed on a certain line.

The ribbon 117, similar to a type-writer ribbon, is wound on the spools 118 and 130

is guided by the fingers 119. The spools are rotatably mounted in the housing by the pins 120 and 130. The notched disk 121 is secured to the spool and the finger 122 is secured to the movable bracket 94. The lever 123 is fulcrumed on the housing and is provided with the toe 124 adapted to raise the lower end of the finger 122 out of engagement with the notches on the disk 121 when the ribbon is not to be moved. The downward movement of the bracket 94 causes the finger 122 to engage one of the notches in the disk 121 and partially rotate the same and consequently the spool 118 to wind the ribbon onto one spool and unwind it from the other.

In order to render the apparatus readily convertible either for embossing or for printing, it is necessary that the ribbon 117 is out of the way of the type dies when printing is not to be performed which feature can be accomplished by moving the ribbon to one side with the fingers, but such method of moving the ribbon is quite inconvenient in operation as well as soiling the fingers and consequent soiling of the work handled with these fingers.

To overcome the above disadvantages, I mount the spools 118 in such a manner that either one or both of them can readily be removed and thereby remove the ribbon also.

The removable mounting of the spools 118 is clearly shown in Fig. 11. Each of the lugs 12 and 13 have the slot 131 in the bottom thereof and extending substantially parallel with the table. The stationary pins 130 are driven into the lugs on one side of the slots 131 and extend into the slots 131 a short distance. The inner end of each of the pins 120 has the enlarged head 132 slidable in the bore 133 in the lugs on the other side of the slots 131 and also extend into these slots a short distance but opposite and in alignment with the pins 130. The outer ends of the pins 120 fit slidably into the respective plates 134 which are secured to the lugs and the knobs 135 are secured to the extreme outer ends of the pins 120. In order to prevent the rotation of the pins 120, the key-ways 136 are provided in the plates 134 and the pins 137 are driven into the knobs 135 to enter the key-ways when the spools are in position. The compression springs 138 are disposed over the pins 120 and between the heads 132 and the plates 134.

The spools 118 have a central bore whereby the same are journaled on the heads 132 and on the pins 130. When it is desired to remove either one or both of the spools 118, it is only necessary to take hold of the knob 135 and pull the pin 120 outward against the compression of the spring 133 until the head 132 recedes into the bore 133 whereupon the spool can be moved longitudinally and off of the pin 130 and removed

out of the slot 131 which is made sufficiently wide to permit of such longitudinal movement of the spool.

As to operation of the guide members; the guide member 107 is moved along the bracket 57 to any desired position corresponding to the point of starting operations sidewise on the object and is locked in position by the screw 113. The guide member 108 is moved along the guide member 107 to any desired position corresponding to the starting point of operation lengthwise of the object and is locked in position by the screw 115.

As to operation of manually moving the table; supposing that a name of ten letters is to be printed on a book; divide ten (ten letters) by two which equals five; then rotate the shaft 74 until the pointer 78 registers with the graduation "5" on the index disk 77; this rotation of the shaft 74 rotates the gear 75 which, in mesh with the rack 56, moves the table accordingly; then proceed with the printing operations; upon completion of these operations it will be found that the printing is spaced symmetrically on each side of the zero line.

As to operation of the automatic table indexing mechanism; after the guide members and the table is manually set as above set forth, each forward and downward movement of the handle 49 and consequent partial rotation of the shaft 48 and the cam 95 operates this mechanism. As soon as this cam 95 rotates, and during the first part of the downward movement of the handle of such rotation, the high point 97 forces the bracket 94 and consequently the push rod 92 downward quickly until the high point 97 is directly under the axis of the shaft 48 as indicated in dot and dash lines in Fig. 8; upon further rotation of the shaft 48, the bracket 94 remains stationary since the face 98 is concentric with the longitudinal axis of the shaft 48. As the rod 92 so moves downward, the outer end of the crank 90 is thereby pushed downward and the shaft 85 is partially rotated. This partial rotation of the shaft 85 moves the upper end of the crank 86 toward the rod 92 and moves the bar 83 in the same direction. As soon as the bar 83 so starts to move (first part of movement of the handle 49, before the die reaches the object on the table), the toe 105 is no longer confined against the bracket 80 and the spring 103 forces the outer end of the finger 102 down into one of the notches in the wheel 79 (dog 100 swivels on the pin 101) as seen in dot and dash lines in Fig. 10, and rotates this wheel one notch thereby also rotating the shaft 74 and the gear 75 which, in turn, moves the table through the rack 56. About the time that the high point 97 has moved the bracket 94 to its lowest position, as shown in dot and dash

lines in Fig. 10, the table is moved to printing position and the pins 106 are moved into two successive notches in the wheel 79, as shown in dot and dash lines in Fig. 10, 5 thereby locking this wheel against further rotation which lock continues until the handle 49 is again returned to inoperative position since the surface 98 is concentric with the shaft 48. As soon as the handle 49 is so 10 returned, the springs 89 and 99 return all of this indexing mechanism back to inoperative position as shown in full lines in the drawings. During this return movement, the toe 105 abuts the bracket 80 and rotates 15 the dog 100, against the action of the spring 103, until the end of the finger disengages the tooth on the wheel 79 to permit manual operation of the table. Each successive stroke or operation of the handle 49 automatically 20 moves the table to the next printing position and indexes and locks it there until the printing is completed.

As to the operation of the clamp frame; the cam 71 is normally held in inoperative position by the toe 72 as previously set forth and the clamp frame is held down upon the table by the springs 62. Upon rotation of the shaft 70, by means of the handles 73, the faces 125 of the cams 71 engage the 25 under sides of the portions 67 and raise this clamp frame above the table as shown in dot and dash lines in Fig. 7. When this frame is raised to its uppermost position, the face 125 of the cams abuts the inner 30 face of the lugs 59, and the points 126 of the cams, now supporting the frame, have traveled beyond the center of the shaft 70 and thereby hold the frame in this position until the shaft is returned to original position 35 by the handles 73. While the clamp frame is in this upper position, the object 63 is inserted between the top of the table and the bottom of the longitudinal bars 64 and 65; upon the return of the shaft to original position as set forth, the springs 62 move this frame downward and clamp the object upon the top of the table.

As to the operation of the type die wheel and lock mechanism, the shaft 32 is rotated 50 to selectively convey one of the type dies into operative position which is indicated when the pointer 47 registers with the particular character on this die. When the type wheel 27 is moved downward by the handle 49, as will appear presently, the index wheel 38 also moves bodily downward and the space between two of the teeth thereof engages the beveled upper end of the lock pin and thereby locks the type wheel in indexed position when the same is moved down almost to the position of contacting the object 63.

It is observed that, in this type indexing mechanism, the beveled end of the lock pin, 55 acting in the beveled spaces between the

teeth on the index wheel 38, will rotate this wheel 38 to proper operating position in case such position has not been accurately attained by the manual operation of the shaft 32. It is also observed that the pins 106 act 70 in a similar manner on the wheel 79.

As to operation of the typing mechanism; when the shaft 48 is rotated by means of the handle 49 being moved forwardly and downwardly as indicated by the arrow, the cam 50, normally held in uppermost position by the pin 127, also rotates in the same direction and thereby moves the plate 51 downward against the action of the springs 33. These springs, in turn, exert a resilient 75 downward pressure on the free end of the type wheel support member and move this end downward which movement also moves the type wheel downward. The impact of the type dies upon the object 63 is thereby cushioned and the depth of the impressions or the embossing is governed by the adjusting screw 128 which limits the rotation of the handle 49.

As previously mentioned, the table indexing mechanism is also operated by the shaft 32. The indexing and locking of the table is performed during the first portion of the downward movement of the type wheel before the dies thereof reach the object 63, and the locking of the type wheel is performed just before the type dies reach the object 63, so that all indexed mechanisms are locked in proper operating position before the operation on the object is actually performed for the purpose of preventing the shifting of either the type die wheel or the table and to produce clean work.

As to operation of the embossing and printing means; as previously mentioned, the ribbon 117 winds and unwinds on the spools 118 and passes between the table and the type wheel opposite the type dies. The type dies themselves are adapted to emboss characters in an object whether the ribbon is in position or not so that characters are embossed only when the ribbon 117 is absent and so that characters are embossed and printed in the object when the ribbon is present.

When it is desired to print characters on the object without embossing the same, the adjusting screw 128 is manipulated so that the handle 49 abuts this screw when the type dies touch the object with the ribbon therebetween so that printing only is accomplished with this apparatus.

By manipulation of the screw 128 any desired depth of embossing may be attained within range of the apparatus either with or without printing.

The machine shown and described is not the only embodiment of my invention. I may make various modifications within the scope of the appended claims. For conven-

ience and to reduce the number of claims, I will use the expressions "type dies" "typing means" or other similar terms or expressions which include any sort of dies or means adapted to the present invention either to print or to type or to impress or to emboss or to print and type and emboss characters upon any object susceptible to such operations provided any particular claims do not 10 definitely describe such elements.

Without limiting myself to the precise construction and arrangement of elements shown and described,

I claim:

1. An apparatus of the character described, including, a base, a bracket extending rearwardly and upwardly from each end of said base, a lug on the upper end of each of said brackets, a tie bar connecting both of 20 said lugs, a table on said base to support the object to be operated upon, a type support member having one end thereof hinged to one of said lugs and the other end thereof guided in the other of said lugs, and a type 25 wheel mounted in said type support member intermediate the ends thereof and movable toward and away from said table.

2. An apparatus of the character described, including, a base, a bracket extending rearwardly and upwardly from each end 30 of said base, a lug on the upper end of each of said brackets and each lug provided with a slot open at the bottom thereof, a table on said base to support the object to be operated upon, a type wheel movable toward and away from said table, a rotatable spool in each of said slots, and a ribbon windable on said spools and extending from one of said 35 spools to the other and the extending portion disposed between the top of said table and the lower edge of said type wheel.

3. An apparatus of the character described, including, a base, a bracket extending rearwardly and upwardly from each end 45 of said base, a lug on the upper end of each of said brackets and each lug provided with a slot open at the bottom thereof, a table on said base to support the object to be operated upon, a type wheel movable toward and away from said table, a rotatable spool in each of said slots, a ribbon windable on said 50 spools and extending from one of the spools to the other and the extending portion disposed between the top of said table and the lower edge of said type wheel, and at least one of said spools removably mounted in one of said slots to permit the removal of said ribbon when embossing without printing is to be performed by the apparatus.

4. An apparatus of the character described, including, a base, a bracket extending rearwardly and upwardly from each end 60 of said base, a lug on the upper end of each of said brackets and each lug having a pair of downwardly projecting ears to form a slot

open at the bottom thereof, a table on said base to support the object to be operated upon, a type wheel movable toward and away from said table, a pin extending through each of said pairs of ears and across the slots thereof, a rotatable spool on each of said pins in each of said slots, a ribbon windable on said spools and normally extending from one of said spools to the other and the extending portion disposed between the top of said table and the lower edge of said type wheel.

5. An apparatus of the character described, including, a housing, a table on said housing to support the object to be operated upon, a type support member having one end thereof hinged to said housing and the other end thereof free to move toward and away from said table, means for moving said free end, and resilient means interposed between said free end and said means for moving the same.

6. An apparatus of the character described, including, a housing, a table on said housing to support the object to be operated upon, type dies mounted in a movable type support member mounted in said housing, and means for elastically moving said type support member toward said object; said elastic means including, a plate mounted to move vertically, guide pins secured to said plate and guided in said type support member, springs between said plate and said type support member, and a cam to operate said plate to move the same toward said type support member.

7. An apparatus of the character described, including, a housing, a table on said housing to support the object to be operated upon, type dies mounted in a movable type support member mounted in said housing, and means for elastically moving said type dies toward and away from said object; said elastic means including, a plate mounted to move vertically, guide pins secured to said plate and guided in said type support member, springs between said plate and said type support member, a cam to operate said plate to move the same toward said type support member, and a spring having one end thereof secured to said housing and the other end thereof secured to said type support member to move said type dies away from said object.

8. An apparatus of the character described, including, a housing, a table on said housing to support the object to be operated upon, a movable type support member mounted in said housing, means for moving said support member toward and away from said object, a shaft journaled in said support member, a type wheel secured to said shaft and provided with type dies, and indexing and locking means for said type wheel; said indexing and locking means including, a

- disk secured to said shaft and provided with characters corresponding to and definitely related to the characters on said dies, a pointer secured to said housing to indicate the relative position of said type wheel, an index wheel secured to said shaft and provided with V notches in the circumferential surface thereof numerically and relatively corresponding to said type dies and said characters, a bracket secured to said housing and provided with a pocket, a spring in said pocket, and an index pin guided in said pocket and provided with a V point adapted to engage one of said notches to correctly index and lock said type wheel in position while said support member is moving downward.
9. An apparatus of the character described, including a housing, a horizontally movable table on said housing to support the object to be operated upon, vertically movable type dies and operating mechanism therefor, means for clamping said object to said table, said clamping means comprising an open frame to permit said dies to reach said object, and a wire secured to each end of said frame and extending longitudinally across the opening of said frame in desired relation to said type dies to indicate on said object where said dies will contact the same.
10. An apparatus of the character described, including, a housing, a horizontally movable table on said housing to support the object to be operated upon, vertically movable type dies and operating mechanism therefor, and means for clamping said object to said table; said clamping means including, an open frame guided in said table and adapted to move up and down in relation thereto, spring means to normally hold said frame downward, a shaft journaled in said table, a cam secured to said shaft near each end thereof to engage and move said frame upward upon rotation of said shaft, and a handle on each end of said shaft to rotate the same.
11. An apparatus of the character described, including, a housing, a horizontally movable table on said housing to support the object to be operated upon, vertically movable type dies and operating mechanism therefor, and means for clamping said object to said table; said clamping means including, an open frame guided in said table and adapted to move up and down in relation thereto, spring means to normally hold said frame downward, a shaft journaled in said table, a handle on each end of said shaft to rotate the same, and a cam secured to said shaft near each end thereof to engage and move said frame upward upon rotation of said shaft; said cam provided with a toe to abut said table to normally retain the same in inoperative position; and said shaft located so that said cam abuts said table to retain said frame in uppermost position after said shaft has been rotated.
12. An apparatus of the character described, including, a base, a table movable longitudinally on said base to support the object to be operated upon, a bracket looped rearwardly and upwardly from each end of said base, a type carrier operatively mounted on the upper portion of said brackets, a type wheel mounted in said carrier and movable toward and away from said table, and means for clamping said object upon said table comprising an open frame to engage said object, a looped bar on each end of said frame each having one end thereof secured to said frame and the other end thereof guided on said table, and the looped portions of said bars adapted to support a rolled up portion of said object and to clear said looped brackets when said table moves longitudinally on the base.
13. An apparatus of the character described, including, a housing, a horizontally movable table on said housing to support the object to be operated upon and provided with a rack, type dies and operating mechanism therefor, and means for automatically indexing said table; said indexing means including, a shaft journaled in said housing, a gear secured to said shaft and meshing with said rack, a notched index wheel secured to said shaft, a connecting bar having one end thereof slidably supported on said housing, a latch dog pivoted on said connecting bar and adapted to engage and disengage said notches in the index wheel, a second shaft journaled in said housing, a crank secured to said second shaft and hingedly connected to the other end of said connecting bar, a second crank secured to said second shaft, a push rod having one end thereof connected to said second crank and the other end thereof guided in said housing and secured to a movable bracket, a spring between said bracket and said housing to normally retain said bracket in uppermost position, and a cam operated by said type die operating mechanism to move said bracket and said push rod downward and index said table.
14. An apparatus of the character described, including, a housing, a table longitudinally movable and indexable on said housing, means for operating said table, a type wheel movable toward and away from said table, an operating handle journaled on said housing, a cam on said handle for moving said type wheel toward said table, spring means for moving said type wheel away from said table, a cam on said handle to operate said table moving means during the first portion of said movement of the type wheel toward the table and to retain this index means in this position during the remainder of said movement of the type wheel toward the table and during the first portion

- of said movement of the type wheel away from the table and to release this index means during the last portion of said movement of the type wheel away from the table.
15. An apparatus of the character described, including, a housing, a table longitudinally movable and indexable on said housing, a type wheel movable toward and away from said table, an operating handle journaled on said housing and provided with means for moving said type wheel toward said table, spring means for moving said type wheel away from said table, a table index means including a toothed wheel and a pivoted dog to operate this toothed wheel, lock means for said table index means including a pin adapted to engage said toothed wheel after said dog has operated the same, and a cam on said handle to operate said table index means during the first portion of said movement of the type wheel toward the table and thereby operate said lock means during the remaining portion of said movement of the type wheel toward the table and during the first portion of said movement of the type wheel away from the table and to release this lock means during the last portion of said movement of the type wheel away from the table.
30. An apparatus of the character described, including a housing, an indexable table on said housing to support the object to be operated upon, type dies movable toward and away from said table, a handle for moving said type dies, and means operated by said handle for indexing and subsequently locking said table in indexed position; said indexing and locking means including, a shaft journaled in said housing, a rack secured to said table, a gear secured to said shaft and in mesh with said rack, a toothed index wheel secured to said shaft, an index bar slidably mounted on said housing and operated by said handle, a dog pivoted on said index bar normally out of engagement with the teeth on said index wheel but engaging said teeth and indexing said table during the first period of operation of said handle, and a stop pin secured to said index bar and engaging said teeth on the index wheel to lock the same in indexed position.
35. An apparatus of the character described, including, a table longitudinally movable and indexable on said housing, a type wheel movable toward and away from said table, an operating handle journaled on said housing and provided with means for moving said type wheel toward said table, spring means for moving said type wheel away from said table, means for indexing said table, an index bar longitudinally movable on said housing, means operated by said handle during said movement toward the table for moving said bar

in one direction, spring means for moving said bar in the opposite direction, means on said bar for operating said means for indexing the table during the first portion of said movement of the bar in one direction, and means on said bar for locking said means for indexing the table during the remainder of said movement of the bar in one direction and during the first portion of said movement of the bar in the opposite direction.

18. An apparatus of the character described, including, an indexable table to support the object to be operated upon, means for indexing said table, and operative connection between said table and said means; said means including a ratchet wheel operatively connected with said operative connection between the table and the means, a stationary bracket, an index bar guided in said bracket and adapted to move longitudinally, means for reciprocating said bar, a dog pivoted on said bar and provided with a finger adapted to engage and disengage the teeth on said ratchet wheel and also provided with a toe to abut said bracket and thereby disengage said finger from said teeth when said bar is near one end of its travel in one direction, a spring to move said finger into engagement with said teeth when said bar begins to move in the opposite direction to index said ratchet wheel, and a pin fixed to said bar and adapted to engage said teeth to lock said ratchet wheel into indexed position when said bar is near the end of said opposite movement.

19. An apparatus of the character described, including, a table to support the object to be operated upon, type dies and operating mechanism therefor for operating on said object, and means for adjustably locating said object in relation to said table; said adjustably locating means including, a guide member slidably longitudinally on said table and one end thereof projecting forward of said table, means on said member to confine one side of said object, a guide member slidably longitudinally on said one end of the first mentioned guide member and one end thereof projecting transversely of said one end of the first mentioned guide member, means on the last mentioned guide member to confine one end of said object, means for securing the first mentioned guide member to said table in adjusted position, and means for securing the last mentioned guide member to the first mentioned guide member in adjusted position.

20. An apparatus of the character described, including, a table to support the object to be operated upon, type dies and operating mechanism therefor for operating on said object, and means for locating differently sized objects on said table; said

locating means including, a bracket secured to said table, a guide member slidable longitudinally on said bracket to adjust side-wise location of said object and provided
5 with an abutment for said object, means for locking said guide member to said bracket, a second guide member slidable longitudinally on the first said guide member to adjust endwise location of said object and
10 provided with an abutment for said object, and means for locking the second said guide member to the first said guide member.

21. An apparatus of the character described, including, an indexable table to support the object to be operated upon, type dies movable toward and away from said table, an operating handle to move said dies toward said table, means for manually indexing said table to approximate typing
25 position, a ratchet wheel associated with said means for indexing the table, a bar slidable in parallelism with said table, a dog pivoted on said bar to engage or dis-

engage said ratchet wheel, means operatively associated with said handle to move 25 said bar and thereby move said dog into engagement with said ratchet wheel and rotate the same to positively index said table prior to contact of said dies with said object, means on said bar to engage at least 30 one of the teeth on said ratchet wheel to lock said table in indexed position after said dog has moved the same into that position but prior to contact of said dies with said object, means for retaining said engaging 35 means in contact with teeth on said ratchet thereby locking said table in correctly indexed position while said dies are contacting said object, spring means for returning said bar to original position when said handle is returned to original position, and a toe on said dog to release the same from said teeth when said bar is returned to original 40 position to permit said table to be indexed manually.

GEORGE W. HEENE.
